UNITED STATES PATENT OFFICE.

CARL F. GOUDY, OF FLUSHING, NEW YORK, ASSIGNOR TO PACENT RADIO CORPORATION, OF NEW YORK, N. Y., A CORPORATION OF DELAWARE.

ELECTRICAL PHONOGRAPH REPRODUCER.

Application filed July 30, 1927. Serial No. 209,500.

The objects of this invention are to provide simple and practical apparatus for combining the effects of an ordinary phonograph and a radio receiving set to secure the enhanced effects of electric phonographic reproduction; to obtain a superior reproduction of this nature and to supply the apparatus for the purpose in a relatively inexpensive form readily applicable to present day phonographs and radio receiving equipment.

The foregoing and other desirable objects are attained by certain novel features of construction, combination and relation of parts, including in particular, an especially effective electromagnetic "pick-up" for substitution in place of the reproducer of the phonograph, an adapter plug insertible in the detector socket of the radio set to carry the vibrations of the pick-up to the amplifying side of the receiver and a volume control connected with the plug to regulate the output.

The drawings accompanying and forming part of this specification illustrate certain practical embodiments and uses of the invention, it being understood that such illustration is primarily for purposes of disclosure and that the actual structure and application of the invention may vary without departure from the true scope of the invention as hereinafter described and broadly claimed.

Figure 1 is a broken part sectional general view of the invention as applied to the phonograph and radio receiving set.

Figure 2 is a vertical sectional view of the pick-up unit.

Figure 3 is a rear view of this unit.

Figure 4 is a side view of the magnet system of the unit.

Figure 5 is an end view of the magnet system.

Figure 6 is an enlarged sectional view as on substantially the plane of line 6-6' of Figure 5, showing particularly the elastic mounting of the "reed" or armature.

Figure 7 is a broken front view illustrating a modification of the unit, adapting it to a record of the "hill and dale" style of cut.

Figure 8 is a broken side view of this construction.

The phonograph which is partly shown in Figure 1 is of the well known construction, including a swinging tone arm 10 and a turn table 11 carrying the record 12. Similarly, the radio receiving set is of the usual form having a detector socket 13 and one or more

stages 14 of audio-frequency amplification connected with a "speaker" 15.

The pick up unit is indicated generally at 16 and is of a form to be readily applied to the tone arm in place of the usual sound box. In the illustration this attachment is effected by means of a spring strap or loop 17 connected with the casing of the unit and adapted to be tightened about the neck of the tone arm by a clamp screw 18.

The magnetic system of the unit is shown as consisting of a single short but powerful permanent horseshoe magnet 19 having U-shaped laminated pole pieces 20, 21 secured in opposition on the legs of the magnet and enclosing between them a magnet coil 22 through which passes the vibrating reed or armature 23 carrying or attached at its lower end to the phonograph needle 24.

A flexible and resilient mounting for the reed is provided in the illustration by squaring the lower portion of the reed at 25 and surrounding this squared portion with an elastic sleeve 26 of rubber or the like, clamped firmly in the space between the opposing squared ends 27, 28 of the pole pieces and the underlying and overlying nonmagnetic blocks or bars 29, 30. These clamp bars 29, 30 are secured together with the intervening portions of the pole pieces and elastically encased shank of the reed therebetween by through bolts 31 and the upper bar 30 is rigidly secured to the polar tips of the magnet, over the outer portions of the pole pieces by through bolts 32. These same bolts are utilized to secure a sheet of insulation 33 at the back of the magnet, carrying the terminals 34 of the coil and also to secure the casing about the magnet structure.

The latter features are particularly shown in Figures 2 and 3 where the casing is indicated as made up of an inclined back wall 35 having an attached substantially horizontal bottom wall 36 and a cooperating cap or cover section 37 hollowed to contain all the mechanism and having spaced wall sections 37, 38 at the back with open slots 39 at the lower ends to receive the bolts 32.

A convenient method of assembly is to first make up the electromagnetic structure in its entirety and to then place the same on the back of the casing with the ends of the bolts 32 projecting through the holes 40 in said back and to then slip the front or cap portion of the casing down over the magnet unit

with the back wall portions 35 sliding between the back of the unit and the back wall of the casing until the slots 39 pass down over the bolt shanks; whereupon the cap screws 41 may be applied to the protruding ends of the bolts to secure the parts firmly together. A hook 42 turned inward and upward from the metal taken out of the cord passage 43 in the back wall engages over the rearward wall 10 portion 44 of the cover section to hold the upper portion of the cover firmly in place and the cap screws 41 rigidly secure the lower part of the cover section.

The nuts 45 on the bolts 32 which secure 15 the terminal base and fasten the pole pieces to the magnet, serve also as abutments, as shown in Figure 2, to hold the magnet structure spaced inwardly away from the case. The upper end of the sheet of insulation 33 20 is shown as folded down over the backs of the coil terminals 34 to prevent accidental connection with the case.

The arms 46 of the pole pieces embracing 25 the upper end of the coil are shown as brought quite closely together over the intervening space in the arch of the magnet to provide a relatively narrow magnetic gap 47 and the reed is shown as having a cylindrical portion extending through the coil, terminating in a 30 flattened end portion 48 having small clearance at both sides of the gap. The lower end of the reed is shown as having a needle receiving socket 49 and a clamp screw 50 for the needle received in said socket, said screw projecting freely through an opening 51 provided 35 in the front wall of the case and the needle similarly projecting freely through an opening 52 in the bottom wall of the case.

The lengths of the free portions of the 40 reed, at opposite sides of the point where it is resiliently gripped, are proportioned to secure a desired leverage ratio so that the lesser vibrations of the needle will be magnified or made fully effective at the gap end of the 45 reed. The angular cross section of the resiliently held portion of the reed permits it to vibrate laterally and restrains axial twisting movements. In the construction illustrated, the pole pieces by reason of their U shape are 50 each enabled to act on opposite ends of the reed, which very materially increases the sensible effects in the coil.

The laminations of the pole pieces are 55 shown as held together at their intermediate and tip portions by rivets 53 which aid in keeping these laminated structures of a uniform thickness so that they can be used as "spacers" to provide a seat between the clamp bars 29, 30 for the squared shank of the reed. 60 The rubber sleeve about the shank, in addition to serving as a resilient pivot for the reed, acts as a compensating medium allowing for a reasonable range of variations and inequalities in the size and fit of the parts, provides a simple, sturdy mounting for the reed

and enables the parts being quickly assembled without any great degree of care or skill.

The connection of the pick up device with the output of the radio set is conveniently effected by means of a plug illustrated at 54 as 70 adapted to be engaged with the detector socket of the receiver and having pins 55, 56 plugging into the output circuit of the detector and hence connecting the pick up directly with the input of the first audio-stage. 75 This plug is shown as containing a small bypass condenser 57 connected between the pin terminal 55 and one of the two terminals on the exposed head of the plug, the other end 80 56 being connected with the other exposed terminal. These plug terminals which are indicated generally by the reference characters 58, 59 are of special construction, consisting in each case of a binding nut cooperating with a squared base 60 turned with a cavity 61 which cuts through the four sides of the base, leaving four corner lugs 62. The terminals of the pick up cord 63 are inserted between certain of these lugs and the terminals of the volume control cord 64 are inserted between 90 neighboring or adjacent lugs so that with the tightening of but these two terminal nuts, both the pick-up and the volume control can be connected with the plug. The volume control which is indicated at 65 may simply 95 be a suitable adjustable resistance device, as shown, connected in parallel across the pick-up.

The apparatus, it will be seen, can be quickly placed in service by simply substituting the pick-up device in place of the sound box of the phonograph and by plugging in the adapter into the detector socket of the receiver. With the radio set turned on and the phonograph started, the volume control may 100 then be adjusted to give the desired volume of sound. The electromagnetic pick-up is sensitive and direct in its action and, aided by the amplifying power of the radio, reproduces the original sounds in their true values, 105 free of distortion.

The same electromagnetic reproducing unit can be used with the vertically cut hill and dale type of record, as shown in Figures 7 and 8 by simply mounting the magnet unit 115 vertically, as by means of a suitable supporting bracket 66 and by providing the armature with a lateral extension 67 connected by a link 68 with the end of the stylus lever 69 pivoted on a horizontal axis 70 to the 120 "floating" weight 71. The laterally extending arm 67 is shown as applied to the armature by having an angular stem 72 at the base of the same, secured in the needle socket by means of the clamp screw 50. Thus the reproducer unit shown may be used without change for either the lateral or the vertical cut forms of records.

As the apparatus only requires a rotating turn-table for the record and a support which 125

will enable the pick-up to traverse the record, it will be seen that the simplest and most inexpensive form of phonograph mechanism may be used with satisfactory results.

- 5 Also, since only the audio-amplifier and speaker of the radio set are used, it is only necessary for the best results that these particular parts be of approved construction. Instead of being part of a radio receiving 10 set, the audio-amplifier may be in the form of a separate, simple audio-unit. The practical essentials of the apparatus will thus be seen to be relatively simple and inexpensive.

15 What is claimed is:

1. An electromagnetic reproducer comprising a permanent magnet, pole pieces applied thereto and having portions spaced to afford a seat therebetween, clamp bars bearing on opposite faces of said pole pieces and thereby maintained in definitely spaced relation by said pole pieces, said clamp bars closing opposite sides of the seat between the pole pieces, an armature element having 20 a portion of substantially corresponding cross section disposed in said seat between the clamp bars, elastic material surrounding said portion of the armature and a coil associated with the portion of the armature extending 25 beyond the seat.

2. An electromagnetic reproducer comprising a magnetic reed having means for connecting the same with a phonograph stylus, said reed having a base portion of 30 substantially rectangular cross section and a cylindrical stem terminating in a flattened blade, a coil surrounding said cylindrical portion of the reed, a permanent horseshoe magnet, pole pieces secured to said magnet 35 and having opposed branches forming a magnetic gap for the flattened tip of the reed and opposed branches providing a seat for the substantially rectangular portion of the reed, an elastic sleeve about the angular portion 40 of the reed, clamp bars closing opposite sides of the seat and securing said elastic sleeve in compressed relation with the intervening portions of the pole pieces acting as spacers holding said clamp bars spaced in 45 definite relation.

3. An electromagnetic reproducer comprising a permanent horse-shoe magnet, substantially U-shaped pole pieces secured to the legs of the magnet and having branches 50 opposed in the arch portion of the magnet to form a magnetic gap and branches spaced at the ends of the magnet to provide a seat, a clamp bar overstanding said pole pieces and securing the same to the legs of the 55 magnet, a second clamp bar disposed between the legs of the magnet, said clamp bars bridging the seat between the pole pieces, a magnetic reed adapted for actuation by a phonograph stylus, said reed having a base 60 portion of angular cross section disposed in

said seat, a portion extending therefrom between the pole pieces and terminating in a blade operating in the magnetic gap, an elastic mounting compressed in the seat about the base of the reed and a coil disposed between the opposing hollows of the substantially U-shaped pole pieces and surrounding the extending portion of the reed. 70

4. An electromagnetic reproducer comprising a permanent magnet, laminated pole 75 pieces having separated portions providing a magnetic gap and other separated portions providing a seat, clamp members closing opposite sides of said seat with the laminations of the pole pieces holding said members in 80 definitely spaced relation, a magnetic reed having a shank portion disposed in said seat, a compressible mounting about said shank portion of the reed, said reed having means at one end for the connection therewith of a phonograph stylus and having its opposite end disposed in magnetic relation to the opposed pole pieces and a coil surrounding the intermediate portion of said reed. 85

5. An electromagnetic reproducer comprising a horse-shoe magnet, pole pieces applied to one face of said magnet, a clamp bar overstanding said pole pieces, screws extending through said clamp bar, the pole pieces and the legs of the magnet to secure said parts 90 together, an insulating base secured by said screws at the opposite face of the magnet, a casing for the magnet secured to said screws at the back of said insulating base, a coil disposed between the legs of the magnet and 95 having terminals on said insulating base and a magnetic reed extending through the coil and having a portion resiliently secured to the clamp bar and a portion in magnetic relation to the opposed pole pieces. 100

6. In an electromagnetic reproducer, a horse shoe magnet, pole pieces applied to one face of said magnet, a clamp bar overstanding said pole pieces, screws extending through said clamp bar, the pole pieces and 105 the legs of the magnet to secure said parts together, a casing for the magnet secured to said screws at the back of the magnet, a magnetic reed provided with a needle holder and with an armature portion in magnetic relation to the pole pieces, a bar for clamping said reed to the first clamp bar and screw means extending through the two clamp bars for securing said clamp bars together over the 110 reed. 115

7. In an electromagnetic reproducer, a U-shaped magnet, laminated pole pieces bearing flat against one face of said U magnet, a clamp bar overlying said pole pieces and binding said laminated pole pieces against 115 the face of the magnet, a magnetic reed positioned to cooperate with the pole pieces and a clamp bar secured to the first clamp bar with a portion of the magnetic reed between 120 the two clamp bars and whereby the reed is 130

definitely positioned for cooperation with the pole pieces, said reed having an extension projecting away from the clamp bars and provided with a needle holder.

- 5 8. An electromagnetic reproducer comprising a U-shaped magnet, pole pieces bearing against one face of said magnet, a clamp bar binding said pole pieces against the face of the magnet, a coil resting on said clamp bar, 10 a magnetic reed having a portion projecting from the clamp bar through the coil into magnetic relation to the pole pieces and a second clamp bar holding the reed gripped to the first clamp bar, said reed having an extension 15 projecting from the clamp bars and provided with a needle holder.

9. An electromagnetic reproducer comprising a U-shaped magnet and an electromagnetic unit for attachment thereto, said unit 20 consisting of pole pieces shaped to bear flat against the face of the magnet, a clamp bar secured to the pole pieces and spacing the same in definite relation, a coil mounted on the clamp bar, a magnetic reed having a portion 25 extending through the coil and in electromagnetic relation to the pole pieces, a clamp construction for securing the reed to the clamp bar, said reed having a portion extending from the clamp bar and provided 30 with a needle holder and screw means for attaching the unit as an entirety to the face of the magnet.

10. An electromagnetic reproducer comprising a substantially U-shaped magnet 35 having spaced arms, pole pieces overlying said arms, a clamp bar bridging the arms of the magnet and securing the pole pieces in engagement therewith, a coil mounted on the clamp bar, a magnetic reed having an armature portion at one end in cooperative relation to the pole pieces, a shank portion extending through the coil, a mounting portion at the bridge portion of the clamp bar and a needle holder portion at the opposite 45 end and a clamp device for securing the mounting portion of the reed to the bridge portion of the clamp bar.

11. An electromagnetic reproducer comprising a horse shoe magnet, pole pieces applied to one face of said magnet, a clamp bar overstanding said pole pieces, an insulating base at the opposite face of said magnet, screws extending through said clamp

bar, the pole pieces, the legs of the magnet and said insulating base to secure all of said parts together, a coil having terminals on said insulating base, a magnetic reed having a portion acted on by said coil and a portion in magnetic relation to the opposed pole pieces and means for securing said reed to the clamp bar.

12. In an electric reproducer unit, a magnet, an insulating base at the back of said magnet, pole pieces on the face of said magnet, a clamp bar overlying said pole pieces, a casing and screws extending through said clamp bar, pole pieces, magnet, insulating base and casing for securing all of said parts together.

13. An electric reproducer comprising a 70 horseshoe magnet, pole pieces overlying the face of said magnet, an insulating base plate overlying the back of said magnet and extending across the space between the arms of the same, a coil between the pole pieces in 75 front of said insulating base plate and having terminals on the insulating base, a magnetic reed supported in front of the magnet and the insulating base plate and in operative relation to the coil and pole pieces, a flat 80 back plate at the rear of said insulating base and having a forwardly angled bottom portion extending beneath the magnet and a hollow cover attached to the back wall extending forwardly over the magnet and downwardly to the forwardly angled bottom extension of the back wall.

14. In an electro-magnetic reproducer, a substantially U-shaped magnet, pole pieces consisting of laminations bearing flat against 90 one face of the magnet and having polar extensions projecting across the space between the arms of the magnet, a clamp bar overlying said pole pieces and binding the laminated structure of the pole pieces against the 95 face of the magnet, a coil between the clamp bar and the polar extensions of the pole pieces, a magnet reed having a portion extending through the coil into the region of the polar extensions, and means for securing the reed in supported relation to the clamp bar, said reed having an exposed stylus carrying portion.

In testimony whereof I affix my signature.

CARL F. GOUDY.
